UNITED STATES PATENT OFFICE

GEORGE SIMCHUK, OF MEDICAL LAKE, WASHINGTON, ASSIGNOR OF ONE-HALF TO RAY D. COWEN, OF SPOKANE, WASHINGTON

DAM CONSTRUCTION

Application filed September 4, 1928. Serial No. 303,807.

My present invention relates to an improved dam construction which is especially designed for use in impounding or storing water where a high water level or head is to be maintained in a reservoir. The dam structure which is of masonry and concrete is adapted for construction across a valley to form a natural basin for a reservoir with a spillway or overflow over the crest of the dam to take care of flood conditions should they occur.

Means are provided within the interior construction of the dam for use as wasteways or outlets for water that may seep through the structure of the dam, and seepage around the ends of the dam is provided against, thus eliminating danger of eroding or undermining the dam at its sides or at its bottom.

In carrying out my invention I utilize a curved or approximately semi-circular wall for the main portion of the dam in combination with an oppositely curved or approximately semi-circular wall in the form of an up-stream apron, and these parts at the crest of the dam and at a common, tangential, point on the exterior of the two semi-circular walls, are joined, bridged, or arched by masonry work. The central bridge or arch joining the oppositely curved walls of the dam provides side spaces that are filled with rubble stone or other loose material as gravel and this formation of the dam and filling material are utilized in strengthening the structure as well as in disposing of seepage.

The invention consists in certain novel combinations and arrangements of parts as will hereinafter be more fully set forth and claimed. In the accompanying drawings I have illustrated one complete example of the physical embodiment of my invention wherein the parts are combined and arranged according to the best mode I have thus far devised for the practical application of the principles of my invention.

Figure 1 is a top plan view of a dam structure embodying my invention, parts being broken away and indicated by dotted lines for convenience of illustration.

Figure 2 is a sectional view at line 2—2 of Figure 1.

Figure 3 is an enlarged detail sectional view showing the means for anchoring the ends of the diagonally extending or crossed stress bars constructed within the work.

Figure 4 is a vertical sectional view at line 4—4 of Figure 1 looking toward the up-stream side of the dam.

Figure 5 is a sectional view at line 5—5 of Figure 1 looking toward the downstream side of the dam.

Figure 6 is a transverse vertical sectional view at the center of the structure at line 6—6 of Figure 1.

Figure 7 is a detail sectional view showing the end construction of one of the diagonal or crossed stress bars, and curved, horizontal reinforcing rods in the main portion of the dam structure.

In Figures 2 and 6 the normal water level or head is indicated at the up-stream side of the dam 1, said side being designated as U, while the downstream side of the dam is designated as D. The dam 1 is fashioned of masonry, concrete construction, cement or other suitable material in the form of a curved or semi-circular wall extending across the stream, with a curved, concave slope 2 at its downstream side, and vertical or perpendicular, curved faces at its upstream side. The semi-circular dam is provided with a substantial base 4 of suitable material, and the base merges with a down-stream shelf 5 at the base of the slope 2, said shelf having a declining upper face 6 to carry off seepage or water that leaks or seeps through the dam. Means are provided to prevent seepage or waste of water around the side of the structure at its junction with the walls of the basin, and this seepage or leakage is disposed of through wasteways or channels 7 that extend through the base of the dam, with openings at the up-stream faces 3. These wasteways, as best seen in Figure 2, decline toward the downstream side of the dam and are in position to deliver the waste water upon the top, declining surface of the shelf 5, over which the waste water passes and is thus conveyed from proximity of the dam structure.

The semi-circular main wall 1 of the dam is reinforced by means of a suitable number of

horizontally disposed, curved, reinforcing rods 8 that conform to the shape of the dam, and adjacent their ends these rods have anchoring plates 9 that are retained in place 5 by nuts 10. In this manner the concrete or masonry work of the semi-circular wall is reinforced to withstand stresses and strains imposed against the dam by the impounded water on the up-stream side of the dam, in 10 addition to the strengthening effect attained by the curvature of the semi-circular wall.

At the upstream, or convex side of the semi-circular dam or wall 1, a semi-circular apron 11 is erected of masonry, concrete, or cement, 15 and this apron, as seen in Figure 1 is curved in opposite direction to the curve of the dam 1 and provided with a flat crest 12 conforming to the crest of the dam 1. The upstream slope 13 of the apron curves across the stream 20 to provide an arch structure that receives the force of the pressure of water against the apron, and the latter is joined, at the center of the stream to the dam 1 by an arch or bridge wall 14. This midstream bridge or 25 arch 14 thus connects the dam and apron as integral structures and provides a joint-crest in the mid-stream center of the dam, leaving the sides between the diverging walls of the dam and apron, open, and also leaving 30 open the mid-stream structure of the dam below the bridge 14.

The apron is fashioned with a base 15, and between the base 15 of the apron and the base 4 of the dam, a floor 16 is formed, with its 35 upper surface declining downstream and over which any leakage or seepage may flow to the waste ways 7. The floor 16 extends substantially across the stream between the oppositely curved dam and apron, and this 40 floor supports a filling of rubble stone, gravel, or other comparatively loose filling as 17 that fills the space between the bridge 14 and the floor, and also the lateral U-shaped or V-shaped openings between the diverging walls 45 of the apron and dam at opposite sides of the midstream center of the dam. Thus any seepage or leakage through the wings or ends of the apron, or over the crest of the wings will find its way through the loose filling material 50 to the floor, and thence pass by the wasteways out at the downstream side of the dam, over the shelf or ledge 5.

The bases 4 and 15, the ledge or shelf 5 and the floor 16 thus form substantial foundation 55 elements for the whole structure and the curvature of the apron and dam mutually strengthen one another.

To further strengthen and tie together the apron and dam, I provide crossed or diagonally extending tie bars 18 and 19 that extend from one wing of the apron to an opposite wing of the main wall, crossing through the arch, and also through the filled space beneath the arch or bridge, and these diagonal bars are anchored by plates 20 and nuts 60

21 on the threaded ends of the bars, as seen in Figure 3.

Having thus fully described my invention, what I claim as new and desire to secure by Letters Patent is—

1. A structure comprising oppositely curved walls and a midstream bridge joining the crest portions of said walls at their exteriors, said walls having bases and a floor joining said bases, a suitable filling beneath the bridge and at the sides of the bridge between the diverging wings of the walls, and wasteways from said floor to the downstream side of the structure. 70

2. A structure comprising oppositely curved walls having an integral, midstream joint, a floor between the walls, wasteways from said floor to the downstream side of the structure, a waste shelf at the end of said wasteways, and a suitable filling between the convex portions of said walls. 80

3. A structure comprising a semi-circular dam having a base, a semi-circular apron having a base, and a floor connecting said bases, a midstream bridge integral with the crest portions of said apron and dam, a stone filling on the floor, wasteways from the floor and a waste-shelf at the downstream side of the dam, and crossed diagonally extending tie bars joining said apron and dam. 90

In testimony whereof I affix my signature.

GEORGE SIMCHUK.
